UNITED STATES PATENT OFFICE.

WILLIAM WHITE, OF PASSAIC, NEW JERSEY, ASSIGNOR TO CLARENCE WHITMAN & CO., OF NEW YORK, N. Y.

DESIGN FOR A BED-SPREAD.

SPECIFICATION forming part of Design No. 24,125, dated March 19, 1895.

Application filed January 30, 1895. Serial No. 536,719. Term of patent 3½ years.

To all whom it may concern:

Be it known that I, WILLIAM WHITE, a subject of the Queen of Great Britain, residing in Passaic, Passaic county, and State of New Jersey, have invented and produced a new and original Design for Bed-Spreads, of which the following is a specification.

The leading feature of my design consists of a bed-spread of essentially the configuration and representation shown in the accompanying drawing which exhibits a quarter section of a bed-spread partly in full detail and partly in outline.

In the drawing, *a a a a* are a series of lozenge-shaped ornaments placed side by side. The space between these lozenges is filled in by bands *b b b b* running diagonally of the spread. Adjacent to the last lozenge of the series is a lattice-work band *f* running diagonally of the spread and flanked by a band consisting of checker-board squares *c c c c c*,

bands *d d d d* running between the checker-board squares and with triangles *e e e e e* filling in the remaining space of the band. Adjacent to this last mentioned band is a band *g* into which bands *h i j* run at right angles and extend to a band *k* parallel to the band *g*. Adjacent to these last mentioned bands are parallelograms *l l l* presenting bird's eye effects. All these bands, lozenges, &c., hereinbefore described constitute the field of the spread, which field is bordered by a series of serrated bands *m n o*, the entire spread being bordered by a band *A* presenting a checker-board effect.

35

What I claim is—

The design for a bed-spread, substantially as herein shown and described.

WILLIAM WHITE.
